DESIGN FOR A RADIO CABINET

Louis Kniep, Jr., East Orange, N. J., assignor to
Federal Telephone and Radio Corporation, New
York, N. Y., a corporation of Delaware

Application April 6, 1946, Serial No. 128,341

Term of patent 14 years

(Cl. D56—4)

To all whom it may concern:

Be it known that I, Louis Kniep, Jr., a citizen of the United States, residing at 136A South Munn Avenue, East Orange, Essex County, and State of New Jersey, have invented a new, original, and ornamental Design for a Radio Cabinet, of which the following is a specification, reference being had to the accompanying drawing, forming part thereof.

Fig. 1 is a front perspective view of a radio cabinet, showing my new design;

Fig. 2 is a top plan view of the cabinet; and

Fig. 3 is a view of the right-hand side of the cabinet as shown in Fig. 1. The left-hand side of the cabinet is substantially the same in appearance as the right-hand side.

The characteristic features of my design reside in the portions shown by means of full lines in the drawing.

I claim:

The ornamental design for a radio cabinet, as shown and described.

LOUIS KNIEP, JR.
